UNITED STATES PATENT OFFICE

FREDERIC H. BULLINGER, OF BRONXVILLE, NEW YORK, ASSIGNOR TO WARD LEONARD ELECTRIC COMPANY, A CORPORATION OF NEW YORK

RESISTANCE UNIT

Application filed July 14, 1930. Serial No. 467,674.

This invention relates to resistance units, and particularly to that form in which the resistive conductor is wound upon an insulating tubular support and provided with 5 terminal connections. The invention particularly relates to the support of the terminal leads and to the connection of the leads to the resistive conductor.

Resistance units of this type are usually 10 covered with an adhesive insulating coating such as vitreous enamel, cement and the like; and one object of the invention is to provide an improved form of support for anchoring the terminal leads to the tube and for connection of the resistive conductor to the leads such that there will be no objectionable bump or projection on the tube which cannot be 15 readily covered by the insulating coating. Another object is to avoid a twist in the lead 20 wires where they leave the tube, because such a twist causes a weakening at such points where it is most desirable that the leads should have their full strength and freedom of flexibility without being subjected to additional and unnecessary strains at such 25 points. The lead wire is ordinarily stranded or braided to permit convenient connection of the unit into the desired circuit and to avoid breaking, but continued use causes repeated 30 flexing of the lead wires at the points where they leave the insulating coating on the tube. Thus, the avoidance of any initial strains at such locations will obviously prolong the use 35 of the unit. It has been common to use stranded lead wires which tightly encircle the tube and are twisted together to form their own support upon the tube and to which the resistive conductor is connected. But in 40 firing or baking for maturing the insulating coating on such tube, particularly where the coating is of adhesive vitreous enamel, the difference in expansion between the porcelain tube which is ordinarily used and the lead wires which are usually of copper, results in 45 the encircling lead wires being somewhat loosened during the firing operation and sometimes results in such shifting of the leads on the tube as to cause the unit to be unfit for commercial use, especially where the 50 shifting causes loosening of the resistive con-

ductor. Thus, another object of the present invention is to provide a support and connection of the lead wire such that undesirable looseness or shifting cannot take place.

I accomplish this by use of an auxiliary 55 support for the terminal copper lead which support envelops the tube and also serves to support the copper lead. The auxiliary support is made of a metal having a lower coefficient of expansion than copper, such as iron 60 or steel. Also, by reason of such metal having a higher tensile strength than that of the copper lead wire, it may be made of comparatively small size and yet be amply strong, while at the same time presenting a smaller 65 surface to be covered by the insulating coating, and likewise avoiding undesirable protruding bumps or projections. Another advantage of this invention is that by the use of iron or steel, or similar metal, for the terminal support, the expense is reduced, owing 70 to its lower cost compared to the use of a copper stranded conductor encircling the tube to form the terminal connection. Other objects and advantages of this invention will 75 be understood from the following description and accompanying drawing.

Fig. 1 is a longitudinal section of one embodiment of this invention; Fig. 2 is a side view showing the parts before the application 80 of the insulating coating; and Fig. 3 is a similar view of a modified form.

The insulating tube 1 is preferably of porcelain. The resistive conductor 2 is wound around the tube in successive spaced turns and 85 is connected at the ends, or any desired intermediate point, to the terminals. In the form shown in Fig. 2, the terminal is formed by using an iron or steel wire 3; some other similar metal may be used, but iron or steel is preferable, owing to its high tensile strength and its coefficient of expansion being lower than that of copper. Before the iron wire is mounted on the insulating support, it is wound around 90 or twisted around the copper lead wire by a few turns, the lead wire 4 being preferably of copper and stranded or braided. Fig. 2 illustrates a few turns of the iron wire wound tightly around a part of the lead wire, 95 the latter having an inwardly projecting end 100

4a lying against the body of the tube; and also an outwardly extending end for forming the terminal lead. The wire 3 is firmly secured around the tube by twisting the two ends of 5 the wire together as indicated at 3a. This clamping of the wire around the tube also serves to give the lead wire a firm support on the tube, and it is evident that where the lead wire leaves the tube, there is no twisting strain 10 or tension upon it. One of the ends of the resistive conductor 2 is wound several times around the end 4a of the lead wire and then continues in successive turns around the tube where it is similarly wound around the projecting end 4a of the lead wire at the other end of the tube. The resistive conductor, where it is wound or twisted around the end 4a of the lead, is preferably soldered, brazed, or otherwise intimately connected therewith. 15 The tube is then covered by the insulating material and dried, baked or fired to form the insulating protective coating 5, which is preferably adhesive vitreous enamel. While soft solder may be used to unite the ends of the 20 resistive conductor with the ends 4a of the leads, where the conductor is twisted or wound around these ends, it is preferably, when a vitreous enamel coating is used, to braze, or silver-solder, with a material that is 25 higher in melting point than the temperature at which the enamel is matured, although this is not essential. The right-hand terminal, 30 Fig. 2, indicates the soldering of the end 4a and of the resistive conductor, while the left-hand terminal of Fig. 2 shows the resistive conductor wound around the end 4a before 35 soldering.

The structure shown in Fig. 3 is similar to that already described, except that the twisting of the ends of the iron wire 3 is made at the location of the projecting end 4a of the lead wire; and the two ends of the iron wire and the end 4a are all three twisted together as indicated at 6 in Fig. 3. The resistive conductor is then wound several times around the twisted ends, after which the parts are soldered as indicated at 6a to insure a good electrical connection between the resistive conductor and the terminal lead wire 4. 45 It is apparent that by the use of my improvement, the size of the iron wire 3 may be made comparatively small. The form of anchoring of the lead wire to the wire 3 and to the tube is accomplished without forming any objectionable portion protruding from the tube, and likewise the twisted ends of the iron wire form only a small protuberance, even when the end of the terminal lead is twisted with them, thus permitting the insulating coating 50 to thoroughly cover the parts and securely bind them to the tube and likewise avoiding undue projections which might be subject to hitting or breaking in future handling. The structure is also economical in cost of material, and by reason of its simplicity, is readily 55

and conveniently assembled with low cost of labor. The structure evidently obtains the objects already referred to and is advantageous over prior construction in many respects. 70

Although I have disclosed preferred embodiments of my invention, it is apparent that modifications may be made therein without departing from the scope thereof. 75

I claim:

A resistance device comprising a support, a resistive conductor thereon, a metal wire embracing said support and having its ends twisted together, a conductive wire terminal held in position on said support by said element, said metal wire and conductive wire being wound one around the other, said resistive conductor being directly mechanically and electrically connected with said conductive wire, said metal wire being of a metal having a higher tensile strength and lower coefficient of expansion than the metal of said conductive wire, and an insulating coating covering said resistive conductor and terminal connection. 80 85 90
